UNITED STATES PATENT OFFICE.

FRANK REAUGH, OF DALLAS, TEXAS.

PUMP OR MOTOR.

1,101,329.

Specification of Letters Patent. Patented June 23, 1914.

Original application filed March 2, 1905, Serial No. 248,054. Divided and this application filed April 18, 1910. Serial No. 556,026.

To all whom it may concern:

Be it known that I, FRANK REAUGH, a citizen of the United States, and a resident of Dallas, in the county of Dallas and State of Texas, have invented a new and Improved Pump or Motor, of which the following is a full, clear, and exact description.

This invention relates to certain improvements in that type of mechanism adapted for use in propelling or compressing fluids or in deriving power from the energy of a moving or expanding fluid; that is to say, a type of device adapted for use as a pump, a motor, a compressor or an engine, dependent upon the character of the work to be done and the character of the source of power. My improved device is of the rotary type.

The main objects of the invention are: first, to bring about a perfect balance of all of the moving parts, so that there be no unbalanced eccentric movement and free rotation may be secured; second, to eliminate all reciprocating parts and valves; third, to eliminate all heavy friction from non-working pressure; fourth, to render the device as compact as possible relative to its capacity; and, fifth, to provide a free and direct passage for the moving medium.

This application is a division of my prior application, Serial No. 248,054, filed March 2, 1905, and the present construction is distinguished from that now claimed in said application, by the relative disposition of the individual axes of rotation of the pistons in respect to the axis about which they bodily move. In the present case, all of the axes are parallel, whereas in my prior application, the individual axes of rotation of the pistons are radial in respect to the axis about which the pistons have bodily movement.

Reference is to be had to the accompanying drawings, forming a part of this specification, in which similar characters of reference indicate corresponding parts in all the figures, and in which—

Figure 1 is a longitudinal section through an apparatus constructed in accordance with my invention, the section being taken at right angles to the axes of rotation. Fig. 2 is a section taken on the line 2—2 of Fig. 1; Fig. 3 is a section taken on the line 3—3 of Fig. 2; Fig. 4 is a side elevation of a second form in which no central shaft is em-

ployed; and Fig. 5 is a section taken on the line 5—5 of Fig. 4.

In the specific form illustrated in Figs. 1, 2 and 3, I provide a casing having an outer curved wall C, an end wall E, and an inner core Cr, all of which are rigid in respect to each other. The stationary shaft section B rigidly joints the core Cr to the end wall E and the core Cr, in turn, supports the second stationary shaft section B'. The said stationary shaft sections B and B' are concentric with the central axis of the machine A, while the core Cr is eccentric in respect to said axis A and also to the outer curved wall of the casing C. An annular passage surrounds the core Cr having a contracted portion T, and an opposite enlarged portion U, the centers of which are equidistant from the central axis A. The enlarged portion U serves as a main passage through which the moving medium flows, while the contracted portion, or throat T, serves as a return passage for the pistons. The curves of said passage at the throat T are arcs of circles having centers at central axis A; elsewhere, the curves inclosing said passage are such as are described, or generated by a point on a body (which in this case is the extreme edge of the piston) revolving around the central axis A and simultaneously rotating on its own axis once during two of its said revolutions and in a reverse direction thereto; the axes being parallel and the motions continuous; the outer resulting curve being the interior form of the outer wall C, and the inner resulting curve, or loop, being the outer form of the core Cr of the casing. Two openings or ports O, O, for inlet and outlet to the passage are provided on opposite sides of the portion U. The peculiar form of this casing, with the relation of its outer curved walls and those of its integral, eccentrically placed core is best shown in Figs. 1 and 4.

Revolvously mounted within the outer wall C and concentric with the axis A, is the piston bearing frame DFD', consisting of the two disks D and D' having bearings on the stationary shaft sections B and B', respectively, and being rigidly connected to each other by the portions of the circular flange F. The disk D is recessed, or let into the end wall E, so that its inner surface is flush with that of the remainder of the said end wall and a running fit to the end of the ec- 110

centric core C_r . The opposite disk D' is similarly placed in respect to adjacent parts. The radii of the curvatures of the inner and outer sides of the circular flange F are such that its portions pass through the throat T as a running fit. The pistons P, P' are mounted to rotate within the spaces between the portions of the flange F and are equally distant radially, from the axis A with said flange. In section, each piston is substantially in the form of a flattened rhombus having the obtuse angles rounded. As is shown in Figs. 1 and 4, the rounded center of the piston is a short arc of a circle of a diameter equal to the thickness of the flange F , therefore, the pistons will pass their thin way, or edgewise through the throat T as a running fit, while their width is a running fit radial to the enlarged portion of the passage U and their length is a similar fit between the ends of the casing. From the squared ends of the pistons extend the shaft sections S, S and S', S' , which have bearings in the disks D and D' , respectively. Immediately outside of the disk D' and rigid therewith, is shown a gear case GC . The periphery of this gear case may be adapted for a pulley, or it may be keyed to a shaft at A for the transmission of power to or from the machine. As shown in Figs. 1, 2 and 3, said gear casing is keyed to a rotatable shaft at A , which passes through hollows in the stationary shaft sections B and B' . Within the gear casing GC and at the outer side of the disk D' are the gears G and G , rigidly mounted on the outer ends of the shaft sections S' and S' , respectively. Mounted rotatably on the stub shafts G^2 and G^2 are the intermediate gears G' and G' , which mesh with the gears G and G , respectively. The gears G', G' also mesh with the stationary pinion G^3 , which is rigidly mounted on the stationary shaft section B' . When the piston bearing frame DFD' revolves, the gears G, G and G', G' revolve therewith, and the gears G', G' by meshing with the stationary pinion G^3 are rolled around said pinion and thus are rotated on their own axes, and by meshing with the gears G, G impart to them also and to the pistons connected therewith, a rotary motion, but in an opposite direction. The pinion G^3 has half the number of teeth that the gears G and G each have and therefore will impart to said gears and the connected pistons one-half of a rotation on their own axes during one revolution of same around the axis A . The effect of the intermediate gears G', G' is merely to reverse the direction of rotation. Since the pistons thus turn one-quarter way around on their own axes during one-half of a revolution around the central axis A , they will assume relatively, right angled positions at opposite points in their revolution orbit, and therefore if set to pass

edgewise through the throat T , they will pass broadwise through the enlarged portion of passage U , as is shown in Fig. 1, and as said pistons alternately close the passage U between the two ports O, O , they either impart motion to, or receive motion from the moving medium, while the throat T is continuously closed by the pistons and the intervening flange portions alternately passing therethrough.

Instead of having a central driving shaft extending through the casing as in the specific form illustrated in Figs. 1, 2 and 3, I may mount a shaft eccentrically and outside, as indicated in Figs. 4 and 5. In this form, I construct the casing C' , the core C_r , the flange F' and the pistons P' , of substantially the same form as in the construction above described. A shaft X is mounted in a suitable bearing at one end of the casing and carries a wheel W having cam grooves V extending diametrically thereacross at right angles to each other. Instead of providing gear wheels, each piston at its end is provided with a cam K slideable within its corresponding groove V . The point of intersection of the two grooves is in alinement with the axis of the shaft X , and also in alinement with the axis of the piston when the latter is in its intermediate position within the throat. The pistons are carried by the two disks of the piston-carrying frames D^2 and D^3 , and these rotate about a common center A' , which is out of alinement with the axis of the shaft X . Thus as the shaft X and the wheel W are rotated, the engagement of the blocks K within the grooves V causes the disks D^2 and D^3 to rotate and causes the pistons to rotate in their own axes. The motion of the pistons and curved flange is exactly the same as in the form illustrated in Figs. 1, 2 and 3, except that sliding blocks and cam grooves are substituted for the gear wheels of the form first described. It is evident that one operating mechanism is the equivalent in many respects of the other, and that various other mechanisms might be employed for securing the same result.

Considering straight lines drawn similarly through the centers of the pistons in several positions in this device as radii vectores, it will be seen that they generate from the circle on which they revolve, a Cartesian curve of the fourth class, *i. e.*, a crunodal limaçon. Machines have been constructed with a cardioid form of casing, which is a curve of the third class, but I believe that in the device herein described, the limaçon with its loop curve is used in practical mechanics for the first time. The difference in the mechanism between this and the cardioidal form of machine is radical in that the stationary core, which represents the loop of the curve, firstly, takes

the back pressure, relieving the pistons and bearings of strain, secondly, allows the use of a plurality of pistons, and a consequent large increase in capacity relative to size of machine, and thirdly, of a more substantial construction.

Though either the casing or the piston-bearing frame may revolve relative to the other with similar results, it is preferred in 10 this construction, that the casing be made stationary and the frame the revolving member.

Various changes may be made in the construction and arrangement of the parts without departing from the scope of my invention.

Having thus described my invention, I claim as new and desire to secure by Letters Patent:

- 20 1. The combination of a casing having an integral core and inlet and outlet ports, and pistons mounted to revolve within the casing and simultaneously to continuously rotate on their own axes.
- 25 2. A casing having inlet and outlet ports, a stationary core integral with the casing, pistons mounted to revolve within the casing, and means to continuously rotate the pistons on their own axes simultaneously with their said revolution.
- 30 3. A casing having inlet and outlet ports, a core stationary with the casing and eccentrically located therein, and pistons mounted to revolve through the casing around the core thereof and simultaneously to continuously rotate on their own axes.
- 35 4. The combination of a casing having inlet and outlet ports and a stationary core, and a piston mounted to continuously rotate within the casing, the casing and the piston having a relatively revolutionary movement simultaneously with the rotary movement of the piston.
- 40 5. A casing having a core stationary therewith and inlet and outlet ports, a frame mounted to revolve within the casing, and pistons mounted on the frame to revolve therewith and simultaneously to continuously rotate on their own axes.
- 45 6. A casing having inlet and outlet ports, a stationary core integral with the casing, and pistons mounted to revolve within the casing and simultaneously to continuously rotate on their own axes at one half the speed of their said revolution.
- 50 7. The combination of a casing having inlet and outlet ports, a core within the casing stationary therewith, and pistons mounted to revolve within the casing, and simultaneously to continuously rotate on their own axes in a reverse direction to their said revolution.
- 55 8. A casing having a core stationary therewith and inlet and outlet ports, and continuously rotating pistons within the cas-

ing, the casing and the pistons being in running contact with each other and having relatively revolutionary movement.

9. An annular casing having an integral core eccentrically located therein and inlet and outlet ports, and pistons mounted to revolve through the casing around the core thereof and simultaneously to continuously rotate on their own axes at one half the speed of said revolution.

10. The combination of an annular casing having a stationary core and inlet and outlet ports, and pistons mounted to revolve within the casing and simultaneously to continuously rotate on their own axes at half the speed of said revolution and in an opposite direction thereto.

11. An annular casing having inlet and outlet ports and an integral core, an annular passage of varying dimension within the casing, and pistons mounted to move forward through the passage and to simultaneously continuously rotate on their own axes.

12. An annular casing having an eccentrically located integral core and inlet and outlet ports, a piston bearing frame mounted to revolve within the casing, and pistons mounted on said frame to revolve therewith through the casing and simultaneously to continuously rotate on their own axes.

13. The combination of an annular casing having an eccentrically located integral core and inlet and outlet ports, pistons within the casing, and means to revolve said pistons through the casing around the core thereof and simultaneously to continuously rotate said pistons on their own axes.

14. An annular casing having inlet and outlet ports, the integral core of said casing being eccentrically located therein, a piston bearing frame within the casing, said casing and frame having relatively revolutionary movement, and pistons mounted on the frame to continuously rotate simultaneously with said revolution.

15. An annular casing having an integral, eccentrically located core and inlet and outlet ports, a frame having a circular flange as an integral part thereof mounted to revolve within the casing, and pistons mounted within openings in the flange to continuously rotate therein simultaneously with their revolution therewith.

16. The combination of an annular casing having an integral core and inlet and outlet ports, a flange mounted to revolve within the casing, and a piston mounted within an opening in the flange to revolve therewith and simultaneously to continuously rotate on its own axis in a reverse direction to said revolution.

17. An annular casing having an integral, eccentrically located core and inlet and outlet ports, a flange mounted to revolve with-

- in the casing, pistons mounted within openings in the flange to revolve therewith, and means to continuously rotate the pistons on their own axes once simultaneously with two 5 revolutions with the flange.
18. An annular casing having a stationary core therein, a passage of varying dimension surrounding the core, and two or more pistons mounted to revolve through 10 the passage and simultaneously to rotate on their own axes at a definite speed relative to their said revolution.
19. The combination of a casing whose curves are approximately those of a Cartesian curve with a loop, and pistons mounted 15 to move therethrough in the position of vectors of said curve.
20. A casing having a passage therein of varying interior dimension the curves of 20 whose inner and outer walls at its narrowest part are short arcs of circles, and elsewhere are those of a Cartesian curve of the fourth class, and pistons mounted to revolve through the said passage and to simultaneously 25 so rotate on their own axes as to move edgewise through the narrowest part of said passage and to move broadwise through the opposite part thereof.
21. A casing the curves of whose inner 30 and outer walls are approximately those of a crunodal limaçon and its loop, and a piston mounted to so move within said casing that its edges generate a crunodal limaçon and its loop.
22. The combination of a casing the 35 curves of whose outer walls are approximately those of a limaçon, and the position and curves of whose core are approximately those of the loop of said limaçon, and a plurality 40 of pistons mounted to move through the casing in running contact with both the casing and the core.
23. In a pump, the combination with a 45 casing which contains a pumping chamber whose inner and outer walls lie in a figure of approximately crunodal limaçon form, of pistons and means for moving them through said chamber and at the same time about their axes so that when one of them 50 is at the narrowest part of said chamber and the one opposite it is at the widest part of the chamber the planes in which they lie will be at right angles to each other.
24. A casing, the interior curves of the 55 shell of which are essentially those of a crunodal limaçon, and the exterior curves of the core of which are essentially those of the loop of said limaçon, and pistons mounted to move through the casing in the direction 60 of said curves in running contact with the walls thereof.
25. The combination of an annular casing 65 having inlet and outlet ports, the curves of the outer shell of said casing being of essentially limaçon form and the curves of the
- stationary core thereof being essentially those of the loop of said limaçon, and pistons mounted to revolve within the casing around the core thereof.
26. An annular casing of essentially limaçon form having an integral core of essentially the form and location of the limaçon loop, and pistons mounted to revolve around the loop thereof and simultaneously to continuously rotate on their own axes. 70
27. An annular casing of essentially crunodal limaçon form having inlet and outlet ports and a core of essentially the form and location of the limaçon loop, and continuously rotating pistons within the casing, the casing and the pistons having relatively 75 revolutionary movement.
28. The combination with a casing having inlet and outlet ports of an integral core arranged to produce a passage within the casing around the core, and pistons mounted to revolve through the passage, the inner and outer walls of said passage being parts of a crunodal limaçon curve varied to accommodate the thickness of the piston. 80
29. An annular casing having the core thereof stationary therewith, the curves of said casing and core being respectively similar to a limaçon and its loop, and pistons mounted to revolve through the casing 85 around the core thereof and simultaneously to continuously rotate on their own axes at one half the speed of said revolution and in an opposite direction thereto. 90
30. An annular casing having inlet and 95 outlet ports, the outer shell of said casing being approximately in the form of a limaçon and the stationary core thereof approximately in the form of the loop of the limaçon, a circular revolving flange within the casing, and pistons mounted within openings in the flange to revolve therewith through the casing around the core thereof and simultaneously to continuously rotate on their own axes. 100
31. A pump or motor having a casing of annular interior form the curves of which are those of two similar crunodal limaçons lying side by side, the interval between the origins of said limaçons being determined 105 by the thickness of the pistons of said pump or motor, the left side of the left hand limaçon giving the left side of the casing and the right side of the loop of this limaçon giving the right side of the core of the casing, 110 while the right side of the right hand limaçon and the left side of its loop give respectively the right side of the casing and the left side of its core, one result of this construction being an opening adjacent to the 115 origins of said limaçons which serves as a return throat for the pistons mentioned. 120
32. A casing having interior curves in conformity with portions of those of two crunodal limaçons and their loops, lying 125

side by side, overlapping and having the same bi-tangent, the distance between the origins being fixed by the thickness of a piston which is located within the casing, 5 and the portions of the said geometrical curves to which the casing curves conform being the outermost lines of the limaçons for the outer shell of the casing and the innermost lines of the loops for the stationary 10 core of said casing, whereby an open space

is left at the crunodes for the return passage for the piston mentioned.

In testimony whereof I have signed my name to this specification in the presence of two subscribing witnesses.
